UNITED STATES PATENT OFFICE.

GEORGE H. GLASS AND WALTER CLARK, OF RALEIGH, NORTH CAROLINA.

CIRCUIT-BREAKER FOR TELEPHONE LINES.

SPECIFICATION forming part of Letters Patent No. 340,912, dated April 27, 1886.

Application filed June 23, 1885. Serial No. 169,505. (No model.)

To all whom it may concern:

Be it known that we, GEORGE H. GLASS and WALTER CLARK, of Raleigh, in the county of Wake and State of North Carolina, have invented certain new and useful Improvements in Circuit-Breakers for Telephone Lines; and we do hereby declare the following to be a full, clear, and exact description of the invention, such as will enable others skilled in the art to which it pertains to make and use the same.

Our invention has reference to circuit-breaking devices designed for signaling a subscriber from the main office or exchange; and it consists in the improvements hereinafter fully set forth and explained.

In the accompanying drawing, forming part of this specification, the figure represents a diagrammatic view illustrating the manner of operating the improved pole-changer, which latter is illustrated in section.

In a suitable case, A, is located an electro-magnet, B, consisting of a suitable core, the coils being included in the circuit of a local battery, represented at a, the wires c d of which lead to binding screws e f, from whence wires e' f' lead to the coils of the electro-magnet B; also, within the case A, at each side of the same, is located, respectively, a bracket, C C', each of which terminates in a vertical portion, horizontally perforated, for the passage of a binding-screw, g g', a portion of which projects to form a contact.

D refers to an armature, which is pivotally suspended at its upper end, and is maintained in a vertical position by a weight or pendulum, h, adjustably secured on an extension depending from the armature D. A spring, i'', holds the armature in positive contact with the projecting portion of the screw g. Wires j k, leading from the binding-posts e f, respectively, contact with the pivot of the armature and with the binding-screw g'.

The main or line wire receives its current from the main batteries, and is designated by E, one pole of which is grounded, while the other is led to line by wire m, connecting with the binding-screw m', from whence connection is made with the screw g by means of a wire, n. A binding-post, O, adjacent to the post m',

makes connection with the armature D by 50 means of wire o, while it also connects with the line plate or section F.

In practice the local circuit, represented by the wires leading from the battery a through the coils of the magnet B, is closed, and the 55 magnet represented by B magnetized, thus attracting the armature D, which, upon contacting with the screws g', creates a short-circuit through the wires j and k and armature, thus demagnetizing the magnet B, and enabling the 60 spring i to draw the armature away from the magnet, and causing the armature to contact with the screw g. The latter contact completes the main circuit.

The subscriber having made connection with 65 the plate or section included in the main circuit, and also grounded his instrument, the repeated contacting and receding movement of the armature D results in the main circuit, in which the subscriber's signal or call bell is located, being rapidly broken, but not to such an extent as to interfere with the clear and loud 70 ringing of the bell.

By the construction of the instrument, as herein described, the subscriber's circuit is 75 only broken on one side of the armature, whereas in many of the forms of instruments heretofore used the circuit is broken on both sides, so as to result in the interruptions being too rapid, thus interfering with the clear 80 and loud ringing of the subscriber's bell.

We are aware that in electric bells it has been common to employ the bell-armature to short-circuit the current of the operating-magnet, in order to permit the retraction of the bell- 85 armature.

We claim—

1. The combination, in a telephone-call system, of the main line, a circuit-breaker provided with a single magnet, the coils of which are 90 always in the local circuit, and a short-circuit derived from said local circuit, an armature adapted to be attracted by said magnet and retracted therefrom by a spring, and contacts for said main and short circuits on the opposite sides of the armature, said armature being designed to close said short-circuit, and thereby demagnetize the magnet, whereby the 95

movement of the armature alternately breaks the main and short circuits, substantially as set forth.

2. The combination, in a telephone-call system, of a circuit-breaking device consisting of a single magnet, B, wires $e'f'$, included in the local circuit and forming the coils of said magnet, an armature, D, wires $j\ k$, leading from said local circuit and connecting, respectively, 10 with armature D and with a contact, g' , a contact, g , main battery line connecting therewith, and line-wire connecting with said armature,

whereby said main circuit is broken only on one side of said magnet, substantially as set forth.

In testimony whereof we have signed this 15 specification in the presence of two subscribing witnesses.

G. H. GLASS.
WALTER CLARK.
